PACKING HEAD

Frederick Stone, Los Angeles, Calif., assignor, by
mesne assignments, to Hydril Company, Los
Angeles, Calif., a corporation of California

Application July 6, 1931, Serial No. 548,839

24 Claims. (Cl. 286—16)

This invention relates generally to packing heads, and is more particularly concerned with such heads as are used in carrying out various well drilling operations by the rotary method and 5 against fluid pressure within the well bore.

The head includes novel packing-off arrangements which may be used either singly or in combination to aid in the carrying out of many different operations. I will limit the description 10 to only one or two of these operations, but it will be apparent to those skilled in the art, after reading the description of these chosen operations, how the head may be used to advantage in many other situations. Therefore, my choice of 15 a description of a particular operation is in no way to be considered indicative as a limitation on the uses to which the head may be put.

Likewise, while I have shown two distinct packing assemblies in the head, and while these assemblies are used in combination during certain operations, each assembly has features of novelty and advantage by itself, and in carrying out 20 certain operations, only one or the other of them need be used. Therefore, only such claims as 25 specifically mention these two assemblies are to be considered as limitative on the invention in this regard.

Generally, it may be considered as the object 30 of my invention to provide a packing head of a nature to effect a proper packing around a well pipe passing through the head, with means for maintaining the pack-off as the well pipe is either rotated or moved longitudinally through the head 35 for performing drilling operations or during the setting or removal of the pipe. The packing-off means is of such a nature that it will handle pipe having portions of different outside diameters, for distance, flush joint drill pipe of constant outside diameter having drill collars of 40 larger outside diameter. This example is given by way of illustration, only, and is not to be construed as indicating the adaptability of the head limited to work of such a particular nature.

As a feature of major importance, I have provided in the head a novel type of packer for 45 packing-off the drill stem during rotation and reciprocation thereof. In the usual type of drilling packer, the packing rubber is compressed against the rotating drill pipe by applying pressure from above. With sufficient pressure thus applied to prevent all leakage, the high pressure from the well quickly builds up beneath the 50 packer and acts against the lower end thereof in a manner to compress it to a point where it

is so tightly engaged with the drill stem that said stem quickly burns and wears the rubber away. In contradistinction to such an arrangement, my drilling packer operates generally as follows. The packer rubber is of downwardly pointing 5 conical characteristics, against the inclined wedge faces of which there is applied a contractor adapted, by movement upwardly through the head and with relation to the packer, to contract or constrict the packing rubber about the 10 well pipe.

This contractor is in the form of a piston having a downwardly facing shoulder exposed to the fluid pressure in the head below the plug. By virtue of the pressure thus applied against the 15 contractor, said contractor is moved upwardly in a manner to constrict the packing rubber about the pipe, adjustable means being provided for limiting the upward stroke of the contractor so only a selected amount of the fluid pressure 20 directed thereagainst is effective to constrict the rubber.

In other words, while the full force of the fluid pressure is available for constricting the packing rubber, I have provided means whereby only 25 such a part of this force is effectively applied to the contractor as will give the packer the exact amount of radial constriction necessary to provide a proper seal about the well pipe and yet permit said pipe to be moved with relation to 30 the packer without undue resistance. The constricting movement of the contractor may be regulated easily and with a great degree of accuracy. Furthermore the well pressure acts 35 directly on a comparatively small area of rubber. All these features contribute greatly to the provision of an accurately settable packing rubber, and one which has a relatively great length 40 of useful life under the most severe service conditions.

Below the drilling packer I have provided an 45 inflatable packer which is constructed in a peculiarly novel and effective manner. Its mounting within the packing head is also novel and peculiarly effective for the purpose, but the characteristics of this packer and its mounting are such that they may be discussed to better advantage in the detailed description.

As a further object of the invention, I have arranged the packer assemblies so that may be 50 assembled with the head around the work and removed from such assembly with great ease and dispatch, this being an important feature inasmuch as the bore of the head must be cleared of 55

or furnished with said assemblies during certain operations.

There are many other features of advantage and points of novelty in my packing head but these may be brought out to decidedly better advantage as the detailed description of the head progresses. Reference will be had to the accompanying drawings, in which:

Fig. 1 is a longitudinal, medial section through a packing head embodying my invention, showing the same fully assembled;

Fig. 2 is a reduced section on line 2-2 of Fig. 1;

Fig. 3 is a reduced section on line 3-3 of Fig. 1;

Fig. 4 is a reduced section on line 4-4 of Fig. 1;

Fig. 5 is a detached, top plan view of the setting ring;

Fig. 6 is a reduced elevation of the packing head, parts being in broken away section and showing the lower packer in engagement with a drill collar 20 on the work;

Fig. 7 is an enlarged fragmentary section showing a detail of the packer guard;

Fig. 8 is a view of Fig. 7 looking in the direction of arrow 8;

Fig. 9 is an enlarged fragmentary section showing a detail of the inlet connection to the inflatable packer; and

Fig. 10 is a view of Fig. 9 looking in the direction of arrow 10.

Referring particularly to Fig. 1, the numeral 10 indicates generally my improved packing head, while numeral 11 indicates vertically extending work which passes through the bore 12 of head 10 with annular clearance. In the drawings, work 35 11 is in the nature of a rotary, tubular drill stem or pipe 13 having thereon a drill collar 14 of increased outside diameter. Now it will be understood that the head is adapted to take and operate upon work having other external characteristics, and the particular work shown is to be considered only as illustrative of one type capable of being handled to advantage with my packing head. To those skilled in the art, it will be immediately apparent from a consideration of this 45 single choice for descriptive purposes that many other types of work may be handled to advantage. Likewise, I shall describe only one or two operations to be performed upon the chosen work by the packing head, but this is not intended as indication of the limitation of operability, as will be readily understood.

Head 10 includes a tubular housing generally indicated at 15 (the bore 12 may be considered as the bore of this housing) having in the upper part 55 of its bore a drilling packing assembly generally indicated at 16, and therebeneath a second packing assembly generally indicated at 17, the packer member of the latter being of the inflatable type. During certain operations these assemblies are 60 used in combination, and in other situations they are used singly or independently. Therefore, only such claims as specify the combination of the two packers are to be construed as limited to such an aspect of the invention.

65 For purposes to be described, it is preferable that housing 15 be of two-part characteristics, the lower bowl or sleeve part 18 having internal thread 19 to take the mating threads on the upper sleeve part or cylinder 20. Sleeve 20 is of lesser 70 diameter than bowl 18, the sleeve end thus forming an internal, annular, and downwardly facing shoulder 21 in the enlarged bore portion 22 of the bowl.

The lower end of bowl 18 has an attachment 75 flange 23 for connection to casing length 24. Of

course, any other type connection can be utilized for providing a disconnectible joint between bowl and casing. Length 24 is at the upper end of the well casing (not shown) and usually contains or is connected to a constrictible packer and an underlying drilling valve. Since said packer and valve are no part of the present invention, they are not shown in the drawings, but are mentioned merely to indicate that the head is used to advantage in connection with such a system and to account for the handling of a situation where neither assembly 16 nor 17 are in full effective position to care for the well pressure.

Well pressure stands, of course, in bore 12, and it is the purpose of packer assemblies 16 and 17 15 so to pack-off the space between the housing wall and the work that various operations on the work, such as rotating it or moving it vertically may be carried on without escape of the fluid under pressure between the housing wall and said work. 20 Of course the packers are just as effective when the work is stationary, and therefore the utility of the head is not limited to situations where the work is moving either angularly or axially. The fluid pressure below the packers may be regulated 25 through the use of customary "beans" or choke nipples arranged in the outlet from the casing bore, but such outlet and beans are not shown here since they are no part of the present invention.

30 I will first describe the packing head in fully assembled condition (Fig. 1) setting out the relation and application of the parts to the work, following with a discussion of the disassembling and reassembling procedures during certain 35 illustrative operative changes.

The relatively reduced bore portion 25 of bowl 18 opens upwardly and outwardly at 26 to bore portion 22, there being an upwardly facing annular shoulder 27 at the lower end of bore portion 22, which shoulder preferably is grooved at 28. A gasket 29 is seated on shoulder 27, being deformed and compressed into grooves 28 by downward pressure exerted upon box 30 which makes up a part of packer assembly 17. Box 30 40 is made up of a ring or sleeve portion 31 which has sliding fit in bore 22 and whose inner peripheral face 33 may be considered as a circumferential seat for the packer 34 carried within the box. At the lower end of sleeve or ring portion 31 45 is an internal, annular flange 35 upon which packer 34 rests.

Packer 34 may be described generally as a tubular, ring-shaped bag preferably of rubber and adapted to be extended by internal fluid or gas 55 pressure radially inwardly and outwardly into sealing engagement with work 11 or 16 and seating face 33, respectively. Preferably, though not necessarily, the packing ring 34 is parted at 37, the hollow 36 being closed off at 38 at each side of 60 the parting. However, when the ring or bag 34 is extended by the application of fluid under pressure to hollow 36, the free ends of the rings are brought together sufficiently to provide a proper seal. By virtue of the ring-parting, the packer 65 34 may be stripped from the work or applied to the work (when assembly 17 is lifted clear of the bowl, as will be described) by transverse movement of said packer with respect to the work, thus avoiding the necessity of sliding the packer 70 longitudinally clear of the work, to obvious advantage.

At a point preferably diametrically opposite parting 37, the outer wall of packer 34 is apertured at 39 (Fig. 9) to take a ferrule 40 made up 75

of sleeve 41 and head flange 42. The packer wall is clamped between flange 42 and a nut 43 which is threaded on sleeve 41 at the exterior of the packer. Preferably nut 43 has an annular lip 44 adapted to be pressed tightly into the packer wall. Nut 43 is also provided with a cylindric flange 45 which is taken within opening 46 provided through ring 31, the fit of the flange in said opening preventing relative rotation of the packer and box 30, though not preventing the packer from being removed from the box when the packer is deflated and the assembly 17 is clear of bowl 18.

Opening 46 is in register with a bore 47 and counterbore 48 which extend through the wall of bowl 18, a key 49 permanently carried by bowl 18 projecting into keyway 50 in box 30 to preserve this registration by preventing relative rotation of the bowl and box. Keyway 50 opens to the under face of box 30, thus allowing said box 20 to be raised from and lowered to position in the bowl. The key also acts as a pilot or indicator to aid in the proper placement of the box when the latter is being lowered to position, the box being rotated until the key is taken in the keyway 25 and then dropped to final position.

A nipple 51, leading from any suitable source of controlled fluid or gas pressure (not shown) is adapted to be projected through openings 47 and 46 into disconnectible attachment with ferrule 40, 30 the connection here being shown as mating threads 52. The inner end 53 of nipple 51 is of reduced diameter to leave annular clearance 54 between it and ferrule 40. The nipple bore is closed at 55, but ports 56 put said nipple bore and 35 clearance space 54 into communication whereby fluid admitted to the nipple flows through ports 56, space 54 and into the hollow 36 of packer bag 34 to extend the same. Packing 57 is adapted to be compressed in counterbore 48 by gland 58 to 40 pack off the nipple at its entrance to the bowl.

Attached by screws 59 to the upper end of sleeve 31, is a cover 60 for box 30. Cover plate 60 is in the form of a ring and preferably has threaded bores 61 opening to its upper face to accommodate 45 "pick-up" bolts (not shown) for use when occasion arises for removing box 30 from the bowl. Cover 60 may be considered as an upper internal annular flange.

Packer 34 is preferably rounded off at 62 and 50 63 to facilitate the entrance of work to the bore 64 thereof. When packer 34 is in collapsed condition the diameter of bore 64 is such as to provide annular clearance between said packer and drill stem 13 and to take drill collar 14. However, 55 the range of packer 34 is such that it may not only be constricted about drill collar 14 but also about drill stem 13.

The upper and inner rounded end 63 of packer 34 is preferably internally reenforced by strips of 60 fabric 65, or the like, such reenforcement being provided to prevent deformation of the packer and more particularly to prevent said upper end from being squeezed upwardly between drill stem 13 and the bore of cover ring 60. Though this is 65 not essential in all cases, I sometimes prefer to provide an annular, flexible guard, generally indicated at 66, for the upper end of the packer. The details of this guard are illustrated in Figs. 7 and 8. Guard 66 is made up of an annular series 70 of what may be considered swinging arms 67, the swing characteristic being given by fashioning the arms of resilient material and anchoring their upper ends, only, with respect to the packer 34. Each arm 67 is made up of a plurality of spring 75 leaves 68, 69 and 70 which are bowed as clearly

shown in Fig. 7, their upper ends being anchored to cover ring 60 by a retaining ring 71 and screw 72. The free end of a given, lower leaf 68 is rolled over as at 73 at opposite sides of slit 74. In the roll-over or hollow bead 73 at one side of slit 74 5 is anchored a connecting pin 75 which extends into loose fit with the hollow bead 73 of the adjacent bottom leaf 68. This pin connection between the free ends of the lower leaves continues around guard 66, thus keeping the leaves generally lined up in proper assembled relationship but allowing the guard, as a whole, to expand or contract radially.

Each lower leaf 68 extends over rounded end 63 as clearly shown in Fig. 1, the beads 73 being seated on a complementary annular shoulder 76. With the packer in the condition of Fig. 1, intermediate leaf 69 of any given arm 67 is preferably spaced slightly at its lower end from leaf 68 and stops a little short of bead 73. Leaf 70, in turn, 20 preferably stops a little short of the end of leaf 69. Consequently, when ring 34 is inflated to constrict the packer bore, arms 67 are swung upwardly, the leaves coming progressively into play to resist increasingly any tendency the packer end 25 may have to move upwardly along stem 13. Beads 73 come successively into engagement with the butt ends of leaves 69 and 70, thus further increasing the resistance of the spring arm.

With housing sleeve 20 threaded down to the 30 position of Fig. 1, it will be seen that its shoulder 21 engages the upper face of box-plate 60 to retain the box against upward vertical movement, and to compress longitudinally the gasket 29 and thus effect a fluid-tight seal between said box and 35 the bowl. Preferably there is also provided a gasket 77 between the end of sleeve 20 and the top of box 30, which gasket is compressed between said members to effect a fluid tight seal at the top of the box around the bowl wall. A key block 40 78 is mounted at the free end of a stiff leaf spring 79 which is anchored by screws 80 at its lower end to the outer face of the bowl. When sleeve 20 has been threaded down to clamp box 30 in proper position, spring 79 is allowed to project 45 keys 78 radially into keyway 81 of sleeve 20 (Fig. 3), this key connection thereafter preventing the sleeve from becoming accidentally unscrewed from the bowl.

It will be seen that inflation of packer ring 34 50 is adapted to move the inner and outer peripheral walls of said packer against the work and seating face 33, respectively. Since the packer containing box 30 is sealed at 29 and 77 with respect to the bowl or housing, it will be seen that inflation 55 of the packer effects a seal between the work, and, in effect, the housing.

Sleeve 20 has a downwardly opening cylinder bore 82 and an upwardly opening counterbore 83, there being diametrically opposite and vertically 60 extending ways 84 sunk in the wall defining the counterbore. The upper end of the sleeve is angularly relieved as at 85. Adapted to slide vertically within and removable upwardly through the sleeve bore is a packer-actuating member 86 employed for radially contracting or constricting drilling packer 87 about the work. Member 86 has a lower plunger or piston head 88 which carries piston rings 88', of any suitable nature, to give it close sliding and fluid tight fit within 70 cylinder 82. The lower end of piston head 88 is annularly recessed as at 89 and 90. The extreme end shoulder 91 is adapted to seat on top plate 69 to limit the downward movement of contractor or piston 86 when no fluid pressure is applied from 75

beneath, though in Fig. 1 said contractor is indicated as having been raised by the application of fluid pressure from below to clear end 91 from plate 69.

- 5 Box 30 thus serves as a stop for limiting the downward movement of the contractor, which provision is of convenience from a manufacturing and assembly viewpoint, but it will be readily understood that any other annular shoulder suitably positioned within the housing bore may be utilized as such a limiting stop.

10 Due to the provision of recesses 89 and 90 there is always provided communication from the space between drill stem 13 and packer assembly 17 to 15 the underside of the piston head; that is, to the downwardly facing shoulders defining the recesses. Of course, as soon as contractor 86 has been lifted to the slightest extent, end 91 also becomes effective as a pressure-taking shoulder.

- 20 With packer 34 deflated, it will be seen that well pressure is constantly imposed on the underside of the piston head 88, that is, assuming that the drilling valve and control packer spoken of previously as being in or connected to casing 24, are 25 not elsewhere taking this pressure. The application of this fluid pressure to the lower end of the piston, tends, of course, to move contractor 86 upwardly through the sleeve bore, this action serving to constrict "drilling" packer 87, as will be made 30 evident.

The upper end of contractor 86 inclines upwardly and outwardly, terminating in a cylindrical portion 92 whose upper end face 93 is provided with threaded bores 94 for the application 35 of "pick-out" bolts (not shown). The bore 95 of tubular contractor 86 tapers inwardly and downwardly to provide a conical seating wedge face 96 to take the complementary conical face 97 of packer 87. This packer is made of rubber or the 40 like and is generally in the shape of a tubular, downwardly pointing cone, though near its upper end it has a short cylindrical portion 98 from which extends the inwardly and upwardly inclining conical portion 99. The packer has an axial bore 100 and, at its lower end, a counterbore 101. The tip 102 of the drilling packer is preferably 45 grooved at 103 to provide lips 104 which are spread apart by fluid pressure entering said grooves, the outer lips thus being urged by fluid pressure into 50 engagement with wall 96.

Due to the complementary, inclined walls 96 and 97, it will be seen that relative longitudinal telescopic movement of packer 87 and contractor 86 will result in a wedging of the packer between 55 work 13 and the contractor, the packer being thus radially contracted or constricted tightly about stem 13.

60 Preferably packer 87 is longitudinally parted as at 105, the parting here being shown as angular to reduce to a minimum the danger of undue leakage at the parting when the packer is contracted. The parting of the packer allows said member to be spread open so it may be applied to or removed from the stem by relative movement transversely thereof, rather than requiring that it be slipped endwise over the pipe, an obvious advantage particularly when it is desired to replace worn packers, as will be made evident.

65 The bore 100 of packer 87 is of smaller diameter than the bore of packer 34 when the latter is collapsed. Packer 87 is thus adapted to pack off drill stem 13, but is not normally capable of functioning with respect to drill collar 14.

70 Applied to the upper end of the packer is a 75 washer or adapter 106 and a setting ring 107.

Preferably, both these members are halved to allow their application to or removal from the stem by movement transversely thereof. To hold the halves of ring 107 in proper alignment, there are provided pilot pins 108 (Fig. 5) at their meeting 5 faces.

While it is not at all essential to the invention, considered in its broader aspects, I prefer to interconnect detachably the packer 87, adapter 106 and ring 107, whereby the assembly, as a unit, 10 may be lowered into or raised from the housing. For this purpose, I mould into packer 87 the nuts 109 and provide upwardly opening bores 110 from the nut bores. Cap screws 111 are passed downwardly through ring 107, adapter 106, and bore 15 110; and threadably connected with nuts 109, thus releasably holding the three members in assembly. The screw-taking holes 111 through the ring and adapter are sufficiently larger than the screws to permit horizontal play thereof and thus allow for their movement as set up by constriction of the packer. Ring 107 has threaded bores 112 to receive "pick-up" bolts (not shown).

As was stated above it is not necessary that members 87, 106, and 107 be connected together as 25 a unit, but when such connection is made it is necessary to include in the assembly the depresser ring 113. When the several parts mentioned are not connected by screws 111 the parts may be 30 individually put into and taken from position, depresser ring 113 then likewise being put independently into position.

Ring 113 has an upwardly and inwardly tapering bore 114 which is complementary to and adapted to take packer end 99, downward movement of the ring with respect to the packer thus tending to constrict the upper end of the packer about stem 13. Ring 113 is adapted to rest on top 35 contractor 86 and has a key 115 entered in one of the ways 84 (Fig. 2) to hold said ring from rotation with respect to sleeve 20.

Setting ring or plate 107 has a bore 116 of greater diameter than bore 108, and the ring includes a depending hub portion 117 and an upper, annular flange portion 118 whose under face 119 is complementary to face 85.

Threaded through flange 118 are the several adjusting or setting bolts 120 which are adapted to extend downwardly to a point where they serve 50 adjustably to limit the upward movement of ring 113 and hence of contractor 86 with respect to sleeve 20 and with respect to packer 87, it being noted that setting plate 107, being held from vertical movement with respect to sleeve 20 by means 55 to be described, serves to hold packer 87 from upward bodily movement with respect to sleeve 20.

A bonnet ring 121 is threaded at 122 on sleeve 20 and has an internal annular flange 123 adapted to overlie and engage flange 118. Flange 123 is provided with transverse sockets 124 and diametrically opposite keyways 125 (only one of which appears in the sectional view, Fig. 1) to take external or internal spanner wrenches, respectively, for threadably adjusting the bonnet 65 on sleeve 20. Keys 126 are carried on flat springs 127 which are anchored at 128 to the bonnet, these keys being adapted to be spring-held in keyways 129 beneath shoulders 130 when the bonnet has been threaded to its proper position, the 70 keys thereafter preventing an accidental loosening of the bonnet.

Bonnet 121 serves as a retainer for assembly 75 and for holding ring 107 in such position that it acts as a shoulder against which packer 87 75

is longitudinally pressed during upward movement of compressor 86.

With the parts in the positions shown in Fig. 1, it is assumed that well pressure is applied to piston 88 to hold packer 87 in such engagement with drill stem 13 as to form a proper seal about the drill pipe. The fit is such as will permit rotation or longitudinal movement of the drill stem without burning or unduly wearing the packing rubber and yet allow only such leakage through the packer as will serve as a packer and drill stem lubricant.

It will thus be seen that though the full pressure of fluid within casing 24 is applied to the piston 88, bolts 120 by limiting the upward movement of the piston, allow only such a portion of the pressure to become effective in contracting packer 87 as will preserve exactly the proper degree of packer-contraction about stem 13. Of course, the full well pressure is available to act on the piston to compress packer 87 into an exceedingly tight fit with the work, but screws 120 serve as adjusting means for regulatably utilizing only such a portion of this well pressure as is desired in a given situation. It will be seen that bolts 120 may be adjusted longitudinally to give a very fine degree of packer control.

When work 11 is initially being lowered into the casing, the bore of head 10 will be entirely cleared of the packer assemblies, the method of clearing being later described. This allows relatively large tools to be lowered freely through the head, well pressure being shut off from said head by means of the drilling valve previously mentioned as being in or connected to casing 24 at a point below the head. The packer mentioned above as cooperating with the drilling valve, is then operated to pack off the work about a drill collar extending therethrough, whereupon the drilling valve is opened and the work lowered until all tools larger than the drill collar have passed through the housing 10.

Packer assembly 17 is then inserted, clamped in place, and extended (all in a manner to be described) into engagement with drill collar 14, as indicated in Figure 6. The drilling valve is opened whereby well pressure is admitted to bore 12. Packer assembly 16 is now inserted in a manner to be described and contracted into proper engagement with drill stem 13. The large tools and the drill collar are then lowered until the smaller drill stem is approximately in the position of Fig. 1. Packer 34 is then deflated and the drill stem lowered to working position, whereafter it may be reciprocated or rotated without losing well pressure at the drilling head.

In removing the work from the casing, the same steps are followed but in the reverse order.

When packer 87 finally becomes worn sufficiently to call for adjustment, it is only necessary to back-off bolts 120 slightly, thus raising the limit of upward movement of contractor 86, whereupon said contractor is moved by fluid pressure up to that new limit and consequently radially compresses packer 87 an amount which will compensate for the wear. Likewise, if fluid pressure conditions vary, bolts 120 may be adjusted to maintain a predetermined packer constriction in spite of such variance in fluid pressure.

I will now set forth the steps followed in removing and replacing packer assembly 16, this description serving also to point out certain of the steps followed when it is desired to clear the housing 10 entirely of all packing means and

during the initial assembly of the packer about the work, respectively.

When the wear adjustment provided by bolts 120 has been taken up to a predetermined degree, it is desirable that a new packer 87 be provided or that a thicker adapter 106 (or any other suitable washer) be interposed between setting ring 107 and the top of the packer. In either event, the operation calls for a partial disassembly of the packing head, though the work is still held packed off within the head so that rotation or reciprocation thereof may continue during the exchange or "shimming" of packer 87.

The first step in the operation is to inflate packer 34 into engagement with stem 13 by the admission of controlled fluid pressure through nipple 51. Movement of stem 13 may continue after packer 34 is thus set. Keys 126 are then lifted from ways 129, and bonnet 121 is unscrewed from sleeve 20 and lifted to a height 20 which will permit the packer assembly 16 to be cleared from sleeve 20. Ring 107 and its connected parts then being lifted clear of sleeve 20, screws 111 are removed to permit ring 107, adapter 106 and packer 87 to be stripped transversely from the drill stem. Thereupon either a new packer is substituted or a thicker adapter or other suitable washer material is substituted for or in combination with ring 106 and the parts are again connected in assembly about the drill stem, with bolts 120 screwed down to their limit. The assembly is then dropped into sleeve 20 and the following setting operation carried out.

It will be observed that packer box 30 has been maintained in its original position while assembly 16 was removed, by reason of the fact that sleeve end 21 has not been disturbed.

Bonnet 121 is then threaded down on sleeve 20 to a point where bolts 120 are holding contractor end 91 on plate 60 and where hub 117, 40 by pressing packer 87 downwardly into taper bore 95, gives an initial setting of said packer about work 13, although care is taken not to depress packer 87 sufficiently to constrict it too tightly about the work. Bonnet 121 is then backed off 45 sleeve 20 a slight amount which opens up a vertical gap between flanges 118 and 123 so the piston and packer have a capacity for slight upward movement.

Keys 126 are then returned to their locking 50 positions and packer 34 is deflated. Immediately the fluid pressure raised between packer 86 and stem 13 acts against the lower end of piston 88 and packer 87 to lift the entire assembly until ring flange 118 engages bonnet flange 123. Bolts 55 120 are then backed away slightly to allow the fluid pressure acting on piston 88 to move contractor 86 upwardly with respect to packer 87, remembering that such packer is now held against bodily upward movement by ring 107. 60 This upward movement of contractor 86 radially constricts packer 87 more tightly about the drill pipe, bolts 120 being adjusted to control the length of piston stroke to such a degree that packer 87 will be constricted about the drill stem 65 to an amount which will allow only sufficient leakage of fluid therebetween to serve as a lubricant.

When it is desired to replace packer 34, one first clears bonnet 121 and the drilling packing 70 assembly 16 from sleeve 20, as described above. Contractor 86 is then lifted clear of the sleeve 20 and the sleeve is subsequently unscrewed from bowl 18 by introducing a spanner wrench in keyways 84. Gland 58 and packing 57 are removed 75

from bowl 18 and nipple 51 is disconnected from ferrule 40.

The box 30 is then lifted clear of the bowl, cap 60 unscrewed and raised from the box, proper, and packer 34 is lifted clear of the box and stripped transversely from stem 13, remembering that it is parted at 37 to allow such stripping. A new packer may then be inserted in the box and the entire packing head be reassembled in 10 a reverse order of steps.

I have spoken of lifting out the various interior parts of the packing head. It will be understood that where vertical movement of stem 13 is allowable said stem may be elevated to lift out the 15 various parts by reason of any upwardly facing shoulders thereon, such as presented by the upper end of drill collar 14, which are of larger diameter than the inside diameter of a given head-part.

20 While I have described in detail the removal of the drilling packer and deflatable packer for purposes of replacement or adjustment, it will be understood that when the packing head is to be cleared by final removal of said parts, the disassembly is followed in the order given above.

Likewise, while I have described in detail the insertion of the head parts in connection with their replacement after temporary removal, it will be understood the same order of placement 30 is followed when the packer parts are first assembled about the work.

As stated in the fore-part of this application, the chosen description of a particular type of work handled by the packing head and the particular operations performed by the head in connection with this work, are merely illustrative and not at all exhaustive. However, the chosen description will make it apparent to those skilled in the art how the head may be used to advantage in many other situations and in connection with many other types of work.

While I have shown and described a preferred embodiment of my invention, it is to be understood that various changes in design, structure 45 and arrangement may be made without departing from the spirit and scope of the appended claims.

I claim:

1. In a packing head for well pipe, a tubular 50 housing adapted to take a well pipe through its bore, a radially contractible packer in the housing and about the pipe, said packer being limited as to bodily upward movement along the pipe, a packer-contracter engaged with the packer and 55 movable vertically through the housing bore and effective, by virtue of upward movement with respect to the packer, to contract the packer about the pipe, said contracter having a downwardly facing shoulder exposed to fluid pressure in the head below the packer, a fluid tight seal between the housing and contracter, the packer providing a seal between the contracter and well pipe, and adjustment screws in the housing adjustably limiting the upward movement of the contracter 60 with respect to the packer under the influence of such fluid pressure.

2. In a packing head for well pipe, a tubular 65 housing, a vertically movable, tubular piston in the housing and about the pipe, said piston having fluid-tight, sliding fit in the housing, the piston throughout its length being spaced annularly from the pipe, the bore of the piston tapering inwardly and downwardly, a conical, radially resilient packer fitted in said piston bore about the pipe, said piston having a downwardly facing shoulder exposed to fluid pressure in the head below the packer, a 70 ring about the pipe and above the packer, a bonnet detachably held to said housing, said bonnet overlying said ring to hold said ring in a position to retain the packer against bodily upward movement, and adjusting members carried by and passed through the ring, said members being movable vertically towards and away from the piston to establish adjustably its upper limit of movement.

3. In a packing head for well pipe, a tubular 75 housing, a vertically movable, tubular piston in the housing and about the pipe, said piston having a downwardly facing shoulder exposed to fluid pressure in the head below the packer.

3. In a packing head for well pipe, a tubular 80 housing, a vertically movable, tubular piston in the housing and about the pipe, said piston having a downwardly facing shoulder exposed to fluid pressure in the head below the packer, and adjustable means 85 for limiting upward movement of the piston through the housing with respect to the packer.

4. In a packing head for well pipe, a tubular 90 housing adapted to take a well pipe through its bore, a radially contractible packer in the housing and about the pipe, said packer being limited as to bodily upward movement along the pipe, a packer-contracter movable vertically through the housing bore along the packer, said packer and contracter having coacting inclined 95 faces whereby upward movement of said contracter radially contracts the packer about said pipe; and means acting positively against said contracter for moving said contracter downwardly.

5. In a packing head for well pipe, a tubular 100 housing adapted to take a well pipe through its bore with annular clearance, a radially contractible packer in the housing and about the pipe, a vertically movable, tubular piston encircling the 105 packer, said piston being effective by upward movement to radially contract the packer and having a downwardly facing shoulder exposed to fluid pressure in the head below the packer; and means for moving said piston downwardly.

6. In a packing head for well pipe, a tubular 110 housing, a vertically movable, tubular piston in the housing and about the pipe, there being annular clearance between the piston and pipe, the bore of the piston tapering inwardly and downwardly, a conical, radially resilient packer fitted in said piston bore about the pipe, said piston having a downwardly facing shoulder exposed to fluid pressure in the head below the packer, a ring 115 about the pipe and above the packer, said ring being detachably held to the housing and holding the packer against bodily upward movement, and adjusting members carried by and passed through the ring, said members being movable vertically towards and away from the piston to establish adjustably its upper limit of movement.

7. In a packing head for well pipe, a tubular 120 housing, a vertically movable, tubular piston in the housing and about the pipe, there being annular clearance between the piston and pipe, the bore of the piston tapering inwardly and downwardly, a conical, radially resilient packer fitted in said piston bore about the pipe, said piston having a downwardly facing shoulder exposed to fluid pressure in the head below the packer, a 125 ring about the pipe and above the packer, a bonnet detachably held to said housing, said bonnet overlying said ring to hold said ring in a position to retain the packer against bodily upward movement, and adjusting members carried by and passed through the ring, said members being movable vertically towards and away from the piston to establish adjustably its upper limit of movement.

8. In a packing head for well pipe, a tubular 130

housing adapted to take a pipe through its bore with annular clearance, a packer comprising a ring-shaped bag of flexible material having an opening from its outer wall to the bag-hollow, 5 said packer being disposed within the housing bore, and a flexible annular guard disposed in the housing at an end of the packer, said guard embodying a plurality of resilient arms, each fixed at one end and having its opposite end overlying 10 said end of the packer, and loose connections between said opposite ends of the arms maintaining them in substantial alinement.

9. In a packing head for well pipe, a tubular housing adapted to take a pipe through its bore 15 with annular clearance, a packer comprising a ring-shaped bag of flexible material having an opening from its outer wall to the bag-hollow, said packer being disposed within the housing bore, and a flexible annular guard disposed in 20 the housing at an end of the packer, said guard embodying a plurality of resilient arms, each fixed at one end and having its opposite end overlying said end of the packer, each arm comprising a plurality of bowed leaves.

25 10. In a packing head for well pipe, a tubular housing adapted to take a pipe through its bore with annular clearance, a packer comprising a ring-shaped bag of flexible material having an opening from its outer wall to the bag-hollow, 30 said packer being disposed within the housing bore, and a flexible annular guard disposed in the housing at an end of the packer, said guard embodying a plurality of resilient arms, each fixed at one end and having its opposite end overlying 35 said end of the packer, each arm comprising a plurality of bowed leaves, said leaves being arranged to come successively and accumulatively into play as the resilient arms are flexed.

11. In a device of the character described, a tubular housing adapted to take work through its bore, packing in said housing and about the work, 40 movable, packer-actuating means in the housing and, by virtue of its movement, effective on said packing to vary its packing effect, said actuating means being exposed to fluid pressure in the 45 housing therebelow whereby said pressure tends to move it in a direction to increase the packing effect of the packer, and adjustable means operable for positively limiting the movement of said 50 actuating means in said direction at any selected point irrespective of the value of said fluid pressure.

12. In a device of the character described, a tubular housing adapted to take work through its bore, fluid-pressure actuated packing in said 55 housing and about the work, and a constantly acting control associated with the packing and operable to maintain constant packer actuation under fluid pressure of increasing value.

60 13. In a device of the character described, a tubular housing adapted to take work through its bore, packing in the housing and about the work, a fluid-pressure actuated piston for setting the packing, and an adjustable control associated 65 with the piston and operable to vary the extent of piston actuation under fluid pressure of given value.

14. In a packing head for well pipe, a tubular housing adapted to take a well pipe through its bore, a radially contractible packer in the housing and about the pipe, a packer-contracter engaged with the packer and movable vertically with relation thereto and effective, by virtue of upward relative movement, to contract the packer 70 about the pipe, said contracter having a down-

wardly facing shoulder exposed to fluid pressure in the head below the packer whereby the contracter is adapted to be moved upwardly to contract the packer, the contracter having a given range of upward movement throughout which 5 the contracter is effective to compress the packer, and a control-stop coacting with the contracter when it is below its limit of upward movement to hold the contracter against upward movement therepast irrespective of the value of the fluid-pressure directed against said shoulder, said control-stop being shiftable to vary the extent 10 of upward movement allowed to the contracter under given fluid pressure.

15. In a packing head for well pipe, a tubular 15 housing adapted to take a well pipe through its bore with annular clearance, a radially resilient packer in the housing and about the pipe, and a tubular piston movable vertically with respect to the pipe and engaged with said packer, said piston being effective by upward movement thereof to radially contract the packer about the pipe and having a downwardly facing shoulder exposed to fluid-pressure in the head below the packer, said packer likewise having a downwardly 25 facing shoulder exposed to said fluid-pressure.

16. In a packing head for well pipe, a tubular housing adapted to take a well pipe through its bore with annular clearance, a radially resilient packer in the housing and about the pipe, and a 30 tubular piston movable vertically with respect to the pipe and engaged with said packer, said piston being effective by upward movement thereof to radially contract the packer about the pipe and having a downwardly facing shoulder exposed to 35 fluid-pressure in the head below the packer, the lower end of said packer having an annular groove therein which is likewise exposed to said fluid-pressure.

17. In a packing head for well pipe, a tubular 40 housing, a vertically movable, tubular piston in the housing about the pipe, said piston having fluid-tight, sliding fit in the housing, the piston being spaced annularly, and from end-to-end, from the pipe, the bore of the piston tapering inwardly 45 and downwardly, and a conical, radially resilient packer in said piston bore and about the pipe, said piston and said packer each having downwardly presented faces exposed to fluid pressure in the head below the packer. 50

18. In a device of the character described, a tubular housing, a tubular piston movable vertically through the housing bore, the bore of the piston tapering inwardly and downwardly, a tubular packer within the piston bore and having 55 its opposite ends shaped externally as oppositely pointing cones, the lower, conical end of the packer fitting the taper of the piston bore, and the upper end of the packer extending above the piston, and a ring engaged with the upper end 60 of the piston and having an inwardly and upwardly tapering bore fitting the upper conical end of the packer.

19. In a device of the character described, a tubular housing, a tubular piston movable vertically through the housing bore, the bore of the piston tapering inwardly and downwardly, a tubular packer within the piston bore and having 65 its opposite ends shaped externally as oppositely pointing cones, the lower, conical end of the 70 packer fitting the taper of the piston bore, and the upper end of the packer extending above the piston, a ring engaged with the upper end of the piston and having an inwardly and upwardly tapering bore fitting the upper conical end of the 75

packer, and means adjustably carried by the housing and engaging said ring to limit upward movement of the piston.

20. A tubular packing rubber for packing heads and the like, having its opposite ends shaped externally as oppositely pointing truncated cones, one of the ends being annularly grooved to provide downwardly extending, spreadable lips, the rubber being parted at one side of its bore and from top to bottom thereof with the line of parting extending angularly with respect to the axis of the packing.

21. A tubular packing rubber for packing heads and the like, having its opposite ends shaped externally as oppositely pointing truncated cones, one of the ends being annularly grooved to provide downwardly extending, spreadable lips, the rubber being parted at one side of its bore and from top to bottom thereof with the line of parting extending substantially in the form of a V.

22. A tubular packing rubber for packing heads and the like, having one end thereof shaped as a downwardly pointing cone and an attachment socket in said rubber, the bore of said socket being accessible from the opposite end of the rubber.

23. A tubular packing rubber for packing heads and the like, having one end thereof shaped as a

downwardly pointing cone, the rubber being parted at one side of its bore and from top to bottom, and a pair of threaded sockets in said rubber, one at each side of the line of parting, the bores of said sockets being accessible from the opposite end of the rubber.

24. In a packing head for well pipe, a tubular housing, a vertically movable, tubular piston in the housing and about the pipe, there being annular clearance between the piston and pipe, the bore of the piston tapering inwardly and downwardly, a conical, radially resilient packer fitted in said piston bore about the pipe, said piston having a downwardly facing shoulder exposed to fluid pressure in the head below the packer, a ring about the pipe and above the packer, means suspending the packer from the ring and holding the packer against movement bodily downward from the ring, said ring being detachably held to the housing and holding the packer against bodily upward movement, and adjusting members carried by and passed through the ring, said members being movable vertically towards and away from the piston to establish adjustably its upper limit of movement.

FREDERICK STONE.
